(57) **CLAIM**

The ornamental design for a sink, as shown and described.

DESCRIPTION

In a preferred embodiment, the nature of this product is as a plumbing fixture primarily useful for washing various objects.

FIG. 1 is a right, top, front perspective view of a sink according to my new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a bottom plan view thereof; and,

FIG. 8 is a left, top, front perspective view of an alternative embodiment of my design, the top plan, front elevational, rear elevational, right side elevational, left side elevational and bottom plan views thereof being mirror images of FIGS. 2-7 above.

The broken line representations in the figures are for the purpose of illustration only, and form no part of the claimed design.
